UNITED STATES PATENT OFFICE.

DOUGLAS G. HARVEY, OF DIXON, ILLINOIS.

APPARATUS FOR APPLYING BORDER AND MEASURE MARKS TO FABRICS.

Application filed October 13, 1923. Serial No. 594,242.

The object of my invention is to provide an efficient method and mechanism for applying a distinctive border to one or both edges of woven wire fabric such as wire screen ordinarily used for windows and doors. My invention, however, is applicable for applying such border marking to other fabrics intended for other uses, and comprises the marked fabric as well as the mechanism and method herein described. Several purposes are served by applying such a border to wire screen fabric. A border such as herein described forms a distinctive designation which will serve as a trade-mark to identify the origin of the goods. By forming the border with projecting points or other marks spaced at predetermined and fixed distances, say at intervals of six inches or a foot, means are provided for accurately and speedily measuring the length of fabric taken from the roll in making a sale. If the marking material used for forming the border be of some permanent and waterproof material, it will serve the further purpose of protecting the edge of the screen cloth from rust where it underlies the nailing strip.

Difficulty has heretofore been experienced in applying a border or other designating mark to wire screen on account of the fact that its open mesh of fine wire does not lend itself readily to receiving and holding the material necessary for that purpose. Before proceeding to a detailed description of my method and the mechanism for applying the same, I will briefly outline the character of the method and apparatus in order to facilitate an understanding of the mechanism more particularly described below.

In the manufacture of wire screen, the fabric after being woven and galvanized, painted or otherwise treated, is delivered in the form of a continuous web which is wound in rolls. As herein described, I apply the border marking to the roll after the completion of the operations referred to. I shall herein refer to the medium which constitutes the border either as the marking medium or filler. This marking medium is preferably of such a degree of viscosity as to fill the mesh-openings between the wires, thus forming a continuous border strip upon the fabric as distinguished from a mere coloring of the wires. As the web of screen-cloth is delivered to my improved apparatus, I cause its edge, or each edge, to pass through a groove in the periphery of a ro-

tary marker, the depth of the groove being sufficient to overlap the selvage edge and one or more rows of mesh-openings inside of the selvage edge. Ordinarily the selvage edge consists of one or more wires over which the woof wires are double back and a suitable border is formed by having the marking medium extend inwardly from the edge of the web to an extent sufficient to cover and fill one or more rows of mesh-openings. For measuring purposes I provide projections at every foot which consist of a widening of the border extending inward to about the fourth or fifth warp wire, and midway between the foot designations I widen the border to a lesser extent to form smaller projections designating fractional subdivisions such as three or six inch divisions. The groove in the rotary marker is continuously supplied with the marking medium, and as the edge of the fabric passes through the groove sufficient of the marking medium is conveyed to the edge-portion of the fabric to accomplish the desired effect. The grooved periphery of the marker is provided at suitably spaced intervals with projections which form the measure marks referred to.

As will appear more in detail from the following description of the mechanism, the web of the screen-cloth or other fabric is conveyed through my improved apparatus, the power for moving the fabric being applied to the shaft upon which the completed fabric is wound, or by other means not necessarily forming part of the marking apparatus. The power for operating my improved apparatus is taken from the moving fabric. In order that the measurement marks be properly spaced upon the fabric, it is, of course, necessary that the angular velocity or speed of rotation of the rotary marker bear a fixed relation to the lineal speed with which the fabric passes through the machine. I accomplish this purpose in the machine hereinafter described by the provision in my apparatus of two rollers, one of them preferably having a rubber surface, these rollers engaging the opposite sides of the fabric with spring pressure whereby the peripheral velocity of the rollers is the same as the lineal velocity of the fabric. One of these rollers is connected by positive gearing, such as the toothed wheels and sprocket chain illustrated, with the rotary marker. By this means the angular velocity or speed of rotation of the marker

bears a fixed relation to the lineal velocity of the fabric. The relation between the lineal velocity of the fabric and the peripheral velocity of the marker where it engages the edge portion of the fabric will depend upon the diameter of the rotary marker. Preferably the diameter of the rotary marker is such that its peripheral velocity will be different from the lineal velocity of the fabric, the peripheral velocity of the marker being greater or less than the lineal velocity of the fabric in order that the rotating marker may exert a wiping action upon the edge of the fabric thereby assisting in removing any surplus of the filler or marking medium of which the border is composed. It will readily be apparent that the periphery of the rotary marker may be given a lineal velocity different from the lineal velocity of the fabric without disturbing the fixed relation which must exist between the angular velocity of the marker and the lineal velocity of the fabric which is necessary to the proper spacing of the length designations upon the fabric.

In the drawings—

Fig. 16 is a detail view of a stop-arm for positioning the rotary marker.

Fig. 17 is a plan view of a modified form of rotary marker;

Fig. 18 is a view of a section of screen-cloth with an edge border formed of a non-viscous medium applied by the rotary marker shown in Fig. 17.

The fixed frame of the machine comprises vertical supports 1, 2, 3 and 4, the supports 1, 3, being connected near their upper ends by a horizontal member 5 shown as an angle-iron fixed to angle-brackets 6 secured to the uprights 1 and 3. The main frame also comprises two members designated generally by the numeral 8, one at each side of the machine and bolted to and connecting the uprights 1 and 2, at one side, and 3 and 4 at the opposite side. The outline of the members 8 is best shown in Figure 1. The two side frames, each composed of two uprights joined by one of the members 8, are rigidly connected by the angle-iron 5 above mentioned and also by guide-rods 9, 10. The mechanism for applying the marking medium or filler to the edges of the screen-cloth consists of two separate similar units slidably mounted, one at each side of the machine, upon the guide-rods 9, 10. The carriage or base part 11 of one of the marking units is shown in perspective in Fig. 8, many of the parts being omitted in that view in order to clearly exhibit the form of the supporting or base member of the carriage and its relation to the guide-rods 9, 10, and other associated parts. These carriages 11 serve as supports for the marking mechanisms on opposite sides of the apparatus. Rotatably mounted in the side frame members 8 is a rotatable shaft 12 having a left-hand screw-thread at one end and a right-hand screw-thread at the opposite end which engage respectively correspondingly screw-threaded apertures 14 in the carriages 11, as most clearly show in detail in Fig. 8. Rotation of the hand-wheel 15 which is secured to shaft 12 moves the carriages 11 toward or away from each other to accommodate screen-cloth of different widths.

I will next describe the means for passing the screen-cloth through the machine and the means for driving the marking mechanism by power derived from the movement of the screen-cloth. The web of screen cloth is drawn through my improved apparatus by any suitable means external to the apparatus. In the present instance, the power for moving the screen is shown as derived from the winding-roll 16, shown in Fig. 1. The web of screen-cloth 18 enters the machine from the left as viewed in Fig. 1, passing beneath a guide-roller 17 which extends across the machine from side to side and is journaled in hangers 19 which are secured to and depend from horizontal angle-iron brackets 20 which are secured to the upper surface of cross-member 5 and project toward the end of the machine at which the screen-cloth

enters. After passing beneath the roller 17, the screen-cloth is received between rollers 21, 22, which are in vertical alinement. Roller 21, as clearly shown in Figs. 5 and 7, is journaled in hangers 23 secured to and depending from angle-brackets 24 fixed to cross-member 5. The rollers 21 and 22 are relatively short and placed at the center of the machine in order to permit the carriages 11 with the marking mechanism mounted thereon to be moved toward each other sufficiently to co-act with the edges of narrow webs of screen-cloth. The long roller 17 is not in the path of movement of the marking mechanisms.

The roller 22, as shown in detail in Fig. 7, is journaled at 25 in the forward ends of angle-levers 26, shown also in Figs. 3 and 9. For the purpose of supporting angle-levers 26 and other parts of the machine, I provide four standards 36, two of them fixed to and projecting upward from each of the guide-rods 9 and 10. These standards 36 are best seen in Figs. 3 and 9. Seated upon and secured to the tops of standards 36 is a horizontal plate 35 and an angle-iron 28 is secured to the outer side of the two standards 36 mounted on the guide-rod 9 as appears in Figs. 3 and 9. Standards 27 fixed to and projecting upwardly from the member 28 afford fulcrum bearings at 30 for the angle-levers 26. The lower substantially vertical arms of the levers 26 are connected at their lower ends by a bar 180, which is shown in Fig. 3. Tension springs 38 are connected at one end to the bar 180 and at the other end to guide-rod 9 and have the effect of imposing upward spring pressure on the roller 22.

The upper roller 21 is preferably of metal and the lower roller 22 is provided with a friction surface layer 40, shown in detail in Fig. 7, of rubber or other yielding material. As the screen-cloth 18 passes between the rollers 21 and 22 it rotates the roller 21 with a peripheral velocity equal to the lineal velocity with which the screen-cloth or other fabric is moving, precise equality of these two velocities being insured by the spring pressure with which the screen-cloth is held against roller 21 by the roller 22. The purpose of imparting to roller 21 a peripheral velocity equal to the lineal velocity of the screen-cloth lies in the fact that the movement of the rotary markers which apply the border and measure marks to the screen-cloth is derived from roller 21. After passing the rollers 21, 22, the screen-cloth is supported by a table 42 supported on standards 43 projecting upwardly from plate 35, and as the screen-cloth leaves the machine it passes under roller 44 which is journaled in standards 45 fixed to the upper ends of uprights 2 and 4 by means of angle brackets 46. The roller 44 is provided with project-

ing flanges 47 distributed at intervals throughout the length of the roller and so spaced that the edge portions of all standard widths of screen-cloth lie between adjacent flanges thus keeping the freshly applied and still moist border and measure marks free from contact with the surface of the roller.

As the screen-cloth passes through the apparatus, it is guided and supported at its edges by means carried by the adjustable marker carriages 11 and its edge portions are engaged by the rotary markers. As above stated, the base and some of the principal parts of one of these carriages is shown in perspective in Fig. 8, the marking mechanism being omitted from that view in order to more clearly exhibit other parts.

The base of the carriage 11 consists of a main member, preferably a casting, having upwardly projecting end sections 51, 52 and a downwardly recessed center as clearly shown in Fig. 8. The bearing 53 for the screw-threaded adjustment shaft 12 is formed in the downwardly recessed central part and the apertures through which the supporting guide rods 9 and 10 pass are formed in the lower parts of the end sections 51, 52. A pedestal 54 is fixed to and projects upwardly from the part 51 of the carriage 11, and a vertical stationary shaft 101 is fixed therein. Rotatably mounted on shaft 101 is gearing which derives power from the metal roller 21 above described, which bears upon the upper surface of the moving screen-cloth, and transmits the power so derived to the rotary markers. Description of the means of transmitting power from roller 21 to the marking mechanism will be deferred until after completing the description of certain other parts which are mounted upon the adjustable carriages.

As shown in Fig. 8, a pedestal 50 consisting of a short section of channel iron is mounted upon and fixed to the part 51 of the carriages 11. Upon the upper flange of the channel iron 50 there is secured a guide-plate 56 upon which the edge of the screen-cloth 18 rests as it travels through the machine. It is understood, of course, that the carriage 11 and its associated mechanism is duplicated in right and left relation upon opposite sides of the machine for the purpose of co-operating with the opposite edges of the screen-cloth. At 57, I have shown the guide-plate 56 recessed for the accommodation of the edge-portion of the rotary marker. At its outer edge—that is, the edge remote from the center of the machine—the guide-plate 56 is provided with an upwardly extending flange 58. For the purpose of holding the screen-cloth in contact with the guide-plate 56, I provide a pressure-plate 59 having a vertical flange 120

60 and a horizontal base 61. The ends of the pressure-plate 59 are upturned at 62, 63, and the ends of the pressure-plate 56 are downturned, as indicated at 185, 186, this merely to provide rounded surfaces at the points of entrance and exit of the screen from the guide formed by the plate 56 and pressure-plate 59. The horizontal base 61 of the pressure-plate 59 extends beneath and is secured to a spring-actuated pressure-member 64, the parts 64 and 59 being in effect a single integral member. The pressure-member 64 is provided with a downwardly opening groove 65 which fits over the upwardly directed flange 58 of the plate 56. A bolt 66 is secured at its lower end in guide-plate 56, as appears in Figs. 8 and 13, and projects upwardly through pressure-member 64, the member 64 being vertically 20 25 30 35 40 45 50 55 60 65 70 tent equal to two mesh openings beyond the straight border-portion 93; and the measure-mark 94, shown in Fig. 14, is illustrated as extending inwardly one mesh further than the straight border 93. The measure-mark 95 is also shown as having greater width longitudinally of the screen-cloth than the measure-mark 94. The measure-mark 95 is formed by the larger projection 96—96' of the rotary marker, and the smaller measure-mark 94 is formed by the smaller projection 97—97' of the rotary marker. The large measure-mark 95 may be used to designate intervals of one foot upon the screen-cloth, and the smaller measure-marks 94 to designate six-inch intervals between the foot marks 95. The rotary marker members 82 and 83 may be held in assembled position upon shaft 81 by means of a nut 84 screw-threaded upon the lower end of shaft 81, as shown in Fig. 10. In the operation of the machine the marking-medium or filler is continuously supplied to the basin 87, and in order to provide against the possibility of the filler overflowing the edges of the basin 87, in the event of the rate of supply of filler being more rapid than its consumption, I provide an overflow opening 98 which may take the form of a hollow nipple 99 extending above the bottom of the basin 87 and communicating with an opening in the lower member of the marker. Means hereafter described are provided for receiving any overflow passing from the lower end of the opening 98.

The shaft 81 is rotatably mounted and vertically supported in the free end of an arm 100, shown in Figs. 1, 2, 4, and 5. The arm 100 is rotatably mounted and vertically supported upon the stationary vertical shaft 101, the shaft 101 being fixed in a pedestal 54, clearly shown in Fig. 8, mounted upon the end 51 of the carriage 11. The arm 100 carrying the rotary marker 82—83 is impelled toward the edge of the screen-cloth by means of a tension spring 104. One end of the spring 104 is secured to the arm 100 and the other end to the upper end of the bolt 66, as clearly shown in Figs. 4 and 5. The pressure-roller 21, which receives rotation from the moving screen-cloth, is provided with hollow trunnions 70 which extend through their bearings in the hangers 23, as shown in Fig. 5 and in dotted lines in Fig. 3. These trunnions 70 and the body of the roller 21 are provided with axial bores which form bearings for drive-shafts 71, one at each side of the machine, as shown in Fig. 3. As shown in Figs. 5 and 7, each of the shafts 71 is splined in its bearing in the hollow trunnion 70, the spline and groove being designated by the numeral 110. The shafts 71 are thus non-rotatably connected to the trunnions 70 but are free to slide endwise therein, the length of the shafts 71 being such that

they may slide into the bores in the trunnions 70 and the continuing axial bore in the roller 21 sufficiently to effect the necessary degree of adjustment. At their outer ends the shafts 71 are mounted in bearings 80. The bearings 80 are mounted upon arms 111 which are fixed to and project horizontally from the standards 54, as shown in Figs. 3 and 8. At their outer ends bevel gears 112 are fixed to shafts 71. The shafts 71 are held against endwise movement relative to bearings 80, and hence partake of the movement of the carriages 11 upon the guide-rods 9 and 10 when said carriages are moved toward and away from each other to accommodate different widths of screen-cloth, and during this movement the shafts 71 have a telescopic movement in the hollow trunnions 70 of the roll 21 to which they are splined, as above described. The bevel gears 112 at the ends of shafts 71 mesh with bevel gears 113 which are integral with or rigidly secured to sleeve members 250. Each of the sleeve members 250 is also formed integrally with or has rigidly secured thereto a sprocket wheel 102 as best shown in Figs. 1, 3 and 5, the latter figure showing the construction in detail. Sleeve member 250 is rotatably mounted on fixed shaft 101 and is supported at its lower end upon a ball bearing 251, the raceway for the balls lying between the lower end of the sleeve member and an annular flange formed on shaft 101. The pivoted arm 100, above mentioned as carrying shaft 81, may rest upon and be supported vertically by the upper end of the sleeve member 250. A sprocket chain 170 engages sprocket wheel 102 upon sleeve member 250 and a sprocket wheel 103 fixed to the rotary marker shaft 81. The rotation of roller 21 is thus transmitted through shaft 71, bevel gears 112, 113, sprocket wheel 102, chain 170 and sprocket wheel 103 to rotary marker shaft 81. Stop arms 114, shown in detail in Fig. 16, may be fixed to the arms 100, and fitted with adjustment screws 115 adapted to contact with the cross-member 5 and thereby limit the movement of the arm 100 and the rotary markers 82—83 carried thereby. As above stated, the rotary markers are impelled in a direction toward the edge of the screen-cloth by the tension springs 104 and the stop-arms 114 when used serve to limit their movement in that direction, while the springs 104 permit the stop-arms to move outwardly to accommodate irregularities in the width or movement of the screen-cloth. The stop arm 114 is not essential to the operation of the machine and may be omitted. When so omitted the base of the groove 88—91 in the rotary marker rides against the edge of the screen cloth or other fabric with yielding pressure caused by the spring 104, which while holding the marker in proper relation to the edge of the fabric

permits it to adjust itself to any irregularities in the form of movement of the web.

Any convenient and suitable means may be utilized for the purpose of supplying marking-material to the basins 87 in the upper surfaces of the rotary markers 82-83. In Fig. 3, I have shown a pipe 117 for supplying the marking-medium or filler, this pipe having flexible branches 119, 119, provided with valved outlets 118 discharging through nozzles 120 into funnels 119 carried by pipes 150 mounted on the movable carriages upon which the marking-mechanisms are mounted. The nozzles 120 may be connected to the funnels 119, as indicated in Fig. 3, in such manner that as the marking-mechanism carriages are adjusted toward and from the center of the machine such adjustment will be accommodated by the bending of the flexible tubes 119. For the purpose of catching any overflow from the basins 87 of the rotary markers 82-83 and any drippings, I provide beneath the rotary markers pans 121 provided with downwardly directed outlet pipes 122, the outlet ends of which are over a trough 123 which inclines downwardly from its ends toward its center where a discharge-pipe 124 leads to a tank 125 in which the overflow and drippings are collected and recovered. At the end of the machine at which the screen-cloth enters, one at each side, are guides 125 mounted at their lower ends upon the parts 51 of the carriages 11 and extending outward around the extreme ends of the roller 17 and inward to the cross-member 5 upon which their upper ends rest, as clearly shown in Fig. 7. In Fig. 7, I have shown the screen 18 as entering the machine from a vertical position and passing beneath the roll 17 horizontally through the machine. In operation, however, the screen 18 is not always perfectly taut as it enters the machine, and may in some instances sag more or less and it is for this reason that I provide the edge guides 125.

I provide a scale 160 mounted on the cross member 5, as shown in Figs. 1, 4 and 5, and a cooperating pointer 161 upon and fixed to a part of the marker carriage 11, the purpose of the scale and pointer being to facilitate adjustment of the markers for different widths of screen-cloth.

I will now describe the operation of the mechanism somewhat more in detail than in the introductory part of this specification. The screen-cloth entering the mechanism passes beneath the roller 17 at the left-hand end of the machine as viewed in Figs. 1 and 7. Beyond the roller 17 the screen-cloth enters the side guides formed between the plates 56 and pressure-members 59, and also finds support upon the central table 42, the latter being shown more particularly in Figs. 2 and 9. Passing between the rollers 21 and 22, the screen leaves the machine

passing beneath the roller 44 to the take-up roll 16, the latter being shown only in Fig. 1. As the screen so passes through the machine its movement imparts rotation to the roller 21. The peripheral velocity so imparted to the roller 21 is equal to the lineal velocity of the screen, exact accuracy being insured by the pressure exerted upon the screen-cloth by the yielding roller 22. The rotation of the roller 21 is transmitted through shafts 71, bevel gears 112, bevel gears 113, and sprocket wheels 102 which form part of sleeve members 250, sprocket chains 170 to the rotary markers 82-83. Since the roller 21 is thus positively connected by gearing to the rotary markers 82-83, the angular velocity or speed of rotation of the markers bears a fixed relation to the rotation of said roller 21 and to the lineal velocity of the screen. Manifestly the relation between the lineal velocity of the screen and the peripheral velocity of the markers 82-83 will depend on the diameters of said rotary markers. The diameters of the rotary markers 82-83 are made such that their peripheral velocity will be different from the lineal velocity of the screen. The peripheral velocity of the marker is made greater (or less) than the lineal velocity of the screen, in order that the rotary markers may exert a wiping action on the edge of the fabric, thereby assisting in removing any surplus of the filler or marking medium of which the border is composed. By rotation of the hand-wheel 15, the distance between the rotary markers at opposite sides of the machine is so adjusted that the grooves 88-91 in the rotary markers embrace the edges of the screen-cloth, the radial depth of the grooves 88-91 in the rotary markers being sufficient to overlap the screen-cloth to the extent necessary to impart the marking shown in Fig. 14, or such other width of marking as is desired. As the edge-portions of the screen-cloth pass tangentially through the overlapping parts of the grooves in the rotary markers, the coloring-medium or filler with which the grooves are supplied from the basins 87 through the openings 89 is conveyed to the edge-portions of the screen-cloth, and by reason of its viscosity the filler bridges over and fills the mesh-openings which are overlapped by the marker grooves. This overlap is uniform throughout the periphery of the rotary-markers except for the projecting parts 96-96' and 97-97', which parts overlap to a greater extent and carry the marking material farther from the edge of the screen-cloth, thereby forming the measure marks 94, 95, shown in Fig. 14. Of course, by omitting the projections referred to, simply a border of uniform width would be formed upon the screen-cloth. As above stated, the roller 44 is provided with pro-

jecting flanges 47 so spaced that the edge-portion of webs of screen-cloth of different standard widths always come between adjacent flanges, thereby keeping the newly applied border and measure-marks from contact with the roller, and thus giving the coloring medium or filler sufficient time to dry before contacting with any surface upon which it might offset.

10 I have found that in the operation of my improved machine, it is desirable that the rotary marker have a peripheral velocity different from the lineal velocity with which the screen moves through the machine thereby causing a relative movement between the edge-portions of the screen and the co-acting part of the groove 88-91 in the rotary marker. Such relative difference of velocity, whichever of the two velocities be greater, causes the walls of the groove 88-91 to exert a wiping action upon the edge-portion of the screen-cloth thereby assisting in removing any surplus of the marking material or filler. This difference of velocity, however, is slight and not of sufficient magnitude to injuriously spread the measure-marks longitudinally of the screen-cloth.

15 It will be obvious that in order to insure accuracy in the placing of the measure-marks 94, 95, upon the screen-cloth, it is essential that the velocity of rotation of the rotary markers 82-83 bear an absolutely fixed relation to the lineal velocity with which the screen-cloth passes through the machine. This end is attained by the positive gearing connecting the roller 21 with the rotary markers, this positive gearing comprising, as above described, the shafts 71 which slidably and non-rotatably engage the roller 21, the bevel gears 112, bevel gears 113 and sprocket wheels 102 of the sleeve member 250, and the sprocket chain 170 which engages the sprocket wheels 102 and 103 fixed respectively to the sleeve member and shaft 81, to the latter of which the rotary markers are secured. The slight difference between the peripheral velocity of the rotary markers 82-83 and the lineal velocity of the screen-cloth also has the effect, according to whether the peripheral velocity is greater or less than the lineal velocity referred to, of imposing either an accelerating or retarding force upon the sprocket chain and bevel gear connections above referred to, thereby preventing any possible irregularity in the placing of the measure-marks due to lost motion resulting from the slack in the gearing. The accelerating or retarding force referred to results from the fact that the engagement of the rotary markers with the edge-portion of the screen-cloth constitutes in effect a friction drive, the frictional engagement being increased by the presence of the viscous marking medium or filler.

20 In Figure 17, I have shown a modified form

of marker 260, the periphery of which is indented at 261 and 262, the notch formed at 261 being wider than that at 262. These notches form interruptions in the groove, corresponding to the groove 88-91 of the 70 marker shown in Figs. 10, 11 and 12, and the use of such a marker gives rise to interruptions in the border upon the fabric as shown in Fig. 18. The wider interruption or gap 263 may designate foot intervals and the 75 smaller gaps 264 may designate fractional intervals such as 3 or 6 inches. In Fig. 18, I have shown the marking material as adhering to the wires without bridging over and filling the mesh openings. This form of 80 marking may be desirable in some instances and may be accomplished by using a relatively freely-flowing marking medium which has not sufficient viscosity to bridge over and fill the mesh openings. 85

What I claim as my invention is:

1. In an apparatus of the class described, means for imparting longitudinal movement to a web of fabric, a rotary marker mounted at the side of the path of movement of said 90 web and adapted to engage the edge portion thereof, said rotary marker having its axis of rotation at right angles to the said path of movement.

2. In an apparatus of the class described, 95 means for imparting longitudinal movement to a web of fabric, a rotary marker mounted at the side of the path of movement of said web and adapted to engage both sides of the edge portion thereof, said rotary marker 100 having its axis of rotation at right angles to the said path of movement.

3. In an apparatus of the class described, 105 markers adapted to engage the opposite edge portions of a moving web of fabric, means for adjusting the distance between said markers, and means to cause said markers in all of their adjusted positions to exert yielding pressure against the edges of said fabric in the plane of said fabric. 110

4. In an apparatus of the class described, 115 rotary markers adapted to engage the opposite edge portions of a moving web of fabric, means actuated by the movement of said web for rotating said markers, means for adjusting the distance between said markers, and means to cause said markers in all of their adjusted positions to exert yielding pressure against the edges of said fabric in the plane of said fabric. 120

5. In a mechanism of the class described, 125 means for imparting longitudinal movement to a web of fabric, a rotary marker mounted to engage the edge portion of said fabric, means to impart different peripheral and lineal velocities to said marker and fabric while establishing a fixed relation between the angular velocity of said marker and the lineal velocity of said fabric.

6. In a mechanism of the class described, 130

means for imparting longitudinal movement to a web of fabric, a rotary marker mounted to engage the edge-portion of said fabric, means independent of the relative peripheral and lineal velocities of said marker and fabric to impart one revolution to said marker for a predetermined amount of longitudinal movement of said fabric.

7. In a mechanism of the class described, means for imparting longitudinal movement to a web of fabric, a rotary marker adapted to engage the edge-portion of said fabric, said rotary marker having its axis of rotation at right angles to the plane of said web of fabric, and means actuated by the movement of said fabric for rotating said marker.

8. In a mechanism of the class described, means for imparting longitudinal movement to a web of fabric, a rotary marker adapted to engage the edge-portion of said fabric, said rotary marker having its axis of rotation at right angles to the plane of said web of fabric, and means independent of the engagement of said marker with said fabric and actuated by the movement of said fabric for rotating said marker at an angular velocity directly proportional to the lineal velocity of said fabric.

9. In a mechanism of the class described, means for imparting longitudinal movement to a web of fabric, a rotary marker adapted to engage the edge-portion of said fabric, and means actuated by the movement of said fabric for rotating said marker at an angular velocity directly proportional to the lineal velocity of said fabric but with a peripheral velocity different from the lineal velocity of said fabric.

10. In a mechanism of the class described, means for imparting longitudinal movement to a web of fabric, a rotary marker adapted to engage the edge-portion of said fabric, and a rotary member adapted to be driven by contact with said fabric and to drive said marker.

11. In a mechanism of the class described, means for imparting longitudinal movement to a web of fabric, a rotary marker adapted to engage the edge-portion of said fabric, and a rotary member adapted to be driven by contact with said fabric and to drive said marker with a peripheral speed different from the lineal speed of said fabric.

12. In a mechanism of the class described, means for imparting longitudinal movement to a web of fabric, a rotary marker adapted to engage the edge-portion of said fabric, and a rotary member adapted to be driven by contact with said fabric and to drive said marker with a peripheral speed different from the lineal speed of said fabric but with an angular velocity having a fixed relation to the lineal velocity of said fabric.

13. In an apparatus of the class described, means for imparting longitudinal movement

to a web of fabric, a rotary marker adapted to have direct driving contact with the edge-portion of said web, a rotary friction member adapted to be driven by said web, and gearing connecting said friction member with said marker.

14. In an apparatus of the class described, web-driving means adapted to impart longitudinal movement to a web of fabric, a rotary marker, means for rotating said marker with an angular velocity bearing a fixed relation to the lineal velocity of said web but with a peripheral velocity different from the lineal velocity of said web.

15. In an apparatus of the class described, means for imparting longitudinal movement to a web of fabric, a marking roller mounted at the side of the path of movement of said web, said roller having a recess adapted to engage both sides of the edge portion of said web, and means for supplying filler to the interior of said recess.

16. In an apparatus of the class described, means for imparting longitudinal movement to a web of fabric, a rotary marker mounted at the side of the path of movement of said web, said marker having a groove in its periphery adapted to engage both sides of the edge portion of said web, and means for supplying filler to the interior of said groove.

17. Mechanism for applying a filler to the edge-portion of a fabric comprising a marker having a groove in its periphery, means for supplying filler to said groove, means for rotating said marker, and means for causing the edge-portion of said fabric to pass through said groove with a lineal velocity different from the peripheral velocity of said marker.

18. Mechanism for applying a filler to the edge-portion of a fabric comprising a marker having a groove in its periphery, means for supplying filler to said groove, means for rotating said marker, and means for causing the edge-portion of said fabric to pass through said groove with a lineal velocity different from the peripheral velocity of said marker, and bearing a fixed relation to the angular velocity of said marker.

19. In an apparatus of the class described, a rotary marker mounted on a vertical axis, said marker having a groove in its periphery, and a reservoir on its upper side and ducts extending through said marker from said reservoir and communicating with said groove whereby said groove is supplied from said reservoir, and means for supplying a liquid filler to said reservoir.

20. Mechanism for applying a filler to the edge-portion of a fabric comprising a rotary marker having an undercut groove in its periphery, means for supplying filler to said groove, and means for causing the edge-portion of said fabric to pass through said groove during the rotation of said member.

21. Mechanism for applying a filler to the edge-portion of a fabric comprising a rotary marker having an undercut groove in its periphery, means for supplying filler to said groove, means for rotating said marker, and means for causing the edge-portion of said fabric to pass through said groove with a lineal velocity different from the peripheral velocity of said marker. 65
22. In an apparatus of the class described, means for imparting longitudinal movement to a web of fabric, a rotary marker mounted at the side of the path of movement of said web, said marker having a recess adapted to engage the edge-portion of said fabric, the interior of said recess being of greater width than the thickness of said fabric and the edge-portion of said recess being of substantially the same width as the thickness of said fabric, and means for supplying filler to the interior of said recess. 70
23. In an apparatus of the class described, a rotary marker, part of the periphery of said marker being circular and part projecting radially outward beyond the circular part, there being a recess in said periphery adapted to contain a filler and to convey the same to the edge-portion of a fabric passing through said recess. 75
24. In an apparatus of the class described, a rotary marker, part of the periphery of said marker being circular and part projecting radially outward beyond the circular part, said rotary marker being provided with a groove extending around its periphery adapted to contain a filler and to convey the same to the edge-portion of a fabric passing through said groove. 80
25. In mechanism of the class described, means for imparting longitudinal movement to a web of fabric, a rotary marker adapted to overlap the edge-portion of said web, part of the periphery of said marker being circular and concentric with its axis and part projecting outward radially beyond said concentric part, and means for supplying a marking material to the overlapping part of said marker and conveying the same to said web. 85
26. In mechanism of the class described, means for imparting longitudinal movement to a web of fabric, a rotary marker adapted to overlap the edge-portion of said web, different parts of said marker overlapping said web to different extents, and means for supplying a marking material to the overlapping part of said marker and conveying the same to said web. 90
27. In mechanism of the class described, means for imparting longitudinal movement to a web of fabric, rotary markers, yielding in the plane of said fabric adapted to engage the opposite edges of said fabric, and means for adjusting the distance between said markers. 95
28. In mechanism of the class described, means for imparting longitudinal movement to a web of fabric, rotary markers, yielding in the plane of said fabric adapted to engage the opposite edges of said fabric, means for adjusting the distance between said markers, and means driven by the movement of said web for rotating said markers. 100
29. In a mechanism of the class described, a roller adapted to be rotated by a moving web of fabric, a rotary marker, said rotary marker having its axis of rotation at right angles to the plane of said web of fabric adapted to engage the edge-portion of said web of fabric, and means for transmitting the rotation of said roller to said marker. 105
30. In a mechanism of the class described, a roller adapted to be rotated by a moving web of fabric, rotary markers, said rotary markers having their axes of rotation at right angles to the plane of said web of fabric adapted to engage the opposite edge portions of said fabric, means for transmitting the rotation of said roller to said markers, and means for adjusting the distance between said markers. 110
31. In a mechanism of the class described, a roller adapted to engage and be rotated by the movement of a web of fabric, shafts slidably and non-rotatably engaging the opposite ends of said roller, bevel gears secured to said shafts, counter-shafts and co-acting bevel gears fixed thereon, radial arms pivoted upon said counter-shafts, rotary markers mounted upon said arms and gearing connecting said counter-shafts and rotary markers, and means yieldably impelling said markers toward each other. 115
32. In a mechanism of the class described, a roller adapted to engage and be rotated by the movement of a web of fabric, shafts slidably and non-rotatably engaging the opposite ends of said roller, bevel gears secured to said shafts, counter-shafts and co-acting bevel gears fixed thereon, radial arms pivoted upon said counter-shafts, rotary markers mounted upon said arms and gearing connecting said counter-shafts and rotary markers, and means yieldably impelling said markers toward each other, said markers and counter-shafts being mounted on carriages adjustable transversely of said web of fabric. 120
33. A method of applying border marking to a web of fabric which comprises the operation of moving a fabric through a body of the border marking material only engaging the marginal edge portion of the fabric. 125

Signed by me at Chicago, Illinois, this 13th day of Sept., 1922.

DOUGLAS G. HARVEY.
